UNITED STATES PATENT OFFICE.

DAVID G. LORRAINE, OF LOS ANGELES, CALIFORNIA.

SPRINKLER.

Application filed March 17, 1924. Serial No. 699,627.

This invention relates to sprinkling systems of the type having nozzles normally retracted below the surface to be sprinkled but adapted for automatic elevation to operative position, by the pressure of the water, when the latter is turned on from a central station.

It is the object of the invention to provide a construction whereby the water will be discharged through the nozzles with minimum resistance to the flow thereof, and in an annular spray providing thorough distribution of the water, the construction including improved adjusting means whereby the spray may be regulated from a relatively heavy shower to a fine mist or fog.

It is a further object of the invention to provide means for locking the spray adjusting means of the nozzles, when they have been set to provide the desired spray.

It is a still further object of the invention to provide a construction arranged so as to prevent leakage of the water, thereby assuring discharge of all of the water through the nozzle heads.

It is a still further object of the invention to provide an arrangement whereby the spray nozzles may be conveniently connected to a water main positioned just below the surface of the lawn or the like, while still providing the necessary vertical space for elevation or retraction of the nozzles, and thereby eliminating the necessity for digging a relatively deep ditch when installing the sprinkling system.

The invention will be readily understood from the following description of the accompanying drawings, in which:

Fig. 1 is a vertical section through one of the nozzles of the sprinkling system showing the same in retracted position.

Fig. 2 is an axial section through a nozzle in elevated position.

Fig. 3 is a detail elevation of the nozzle head with the cap removed.

Fig. 4 is a transverse section on the line 4-4 of Fig. 3.

A pipe line 1 is buried a relatively short distance below the surface to be sprinkled, shown as lawn 2, and extends to the various points where sprinklers are to be installed, the flow of water through the pipe being controlled from a central station.

At each point where a sprinkler is to be placed, a fitting 3 is inserted in pipe 1, said fitting having aligned horizontal openings 4

adapted to receive sections of the pipe line, and having a vertical opening 5 at its upper side and a depending pipe 6 at its lower side in alignment with opening 5. The pipe 6 is closed at its lower end and preferably terminates in a point 7 adapted to be driven into the ground.

A bushing 8 is mounted in opening 5, as by threaded connection 9, said bushing having an internal annular shoulder 10, and a nozzle 11 extends through the bushing and is adapted to be retracted within pipe 6 or elevated into position projecting above the bushing.

The lower end of the nozzle is preferably enlarged as shown at 11, and is grooved at the shoulder formed by said enlargement, with a packing ring 12 received in said groove, the parts being arranged so that elevation of the nozzle is limited by abutment of packing 12 against shoulder 10, thereby forming a leak proof joint between the nozzle and fitting 3.

The upper end of nozzle 11 terminates in a conical head 13 having a transverse enlargement 14 at its apex, and a bore 15 extending through the nozzle, opens through the lower end of the latter into pipe 6, and at its upper end terminates in a transverse bore 16 opening in opposite directions through the nozzle at the base of conical head 13. Spiral grooves 17 are formed in the head 13 and communicate at one end with the respective ends of bore 16, said grooves preferably extending approximately half way around the conical head.

The nozzle 11 is threaded below transverse bore 16, and a cap 18 is received over the head of the nozzle and is vertically adjustable relative thereto, by means of a threaded connection 19 between the lower portion of the cap and the threaded end of the nozzle. The upper portion of cap 18 forms an annular space 20 surrounding the conical head of the nozzle, said annular space being closed by the end 21 of the cap which is provided with a restricted central opening 22 adapted to be received over the enlargement 14 at the end of the conical head.

The end 21 of the cap preferably tapers to a reduced thickness from its periphery to its central opening 22, and it will be noted that vertical adjustment of the cap relative to the nozzle, will increase or decrease the annular space between conical head 13 and

the opening 22, so as to regulate the discharge of fluid from the nozzle.

The cap 18 may be locked in adjusted position on the nozzle, by means of a lock nut 23 having threaded engagement 24 with the threaded end of the nozzle below said cap, in order that said nut may be screwed up tight against the under side of the cap.

The parts are so arranged that when 10 water is shut off from pipe 1, nozzles 11 will drop by gravity to telescoped position in pipe 6 as shown in Fig. 1, so that said nozzles are below the surface of the lawn. As soon as water is allowed to flow through pipe 15 1 into pipes 6, the pressure of said water against the enlargements 11 of the nozzles, will elevate the latter to the position shown in Fig. 2, with the upper ends of said nozzles above the surface of the lawn.

20 The water will flow through bores 15 and 16 of the nozzles, and thence into the annular spaces 20 in caps 18, the spiral grooves 17 rotating the water, and the passage between restricted opening 22 and the upper 25 end of the conical head allowing discharge of the water against enlargement 14, so as to break up the flow and discharge the same onto the lawn in an annular spray which may be accurately controlled by adjustment 30 of cap 18.

It will be apparent that various changes may be made in the construction, combination, and arrangement of parts as thus described without departing from the spirit 35 of the invention.

What is claimed is:

1. A sprinkling system comprising a fluid

conduit, a fitting in said conduit having an opening at its upper side and a hollow member depending from its lower side in vertical alignment with said opening, said hollow member being closed at its lower end and forming a tapering spike adapted to be driven into the ground for anchoring said fitting and said fluid conduit below the surface of the ground with said opening in alignment with a bore extending from the surface of the ground to said opening, a bushing in said opening, a pipe in said fitting projecting through said bushing and normally telescoped in said hollow pipe below the surface of the ground, a nozzle on the upper end of said pipe, an abutment surface at the lower end of the nozzle pipe adapted to be impinged by fluid flowing through said hollow member and said nozzle pipe for elevating the latter into operative position above the surface of the ground, and a shoulder on the nozzle pipe engaging the bushing for limiting elevation of the nozzle pipe.

2. A sprinkling system comprising a fluid conduit having a depending off-set forming a tapering spike adapted to be driven into the ground, and a nozzle pipe fitting loosely in said off-set and normally telescoped therein, and having an abutment surface adapted to be impinged by fluid flowing through said off-set and said nozzle pipe, for elevating the latter into operative position above said off-set.

In testimony whereof I have affixed my signature to this specification.

DAVID G. LORRAINE.
